CLAIM

The ornamental design for a waterproof backpack, as shown and described.

DESCRIPTION

FIG. 1 is a perspective view of a waterproof backpack showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a rear, top, and right side perspective view thereof.

In the drawings, the broken lines illustrate portions of the article which form no part of the claimed design.
